UNITED STATES PATENT OFFICE.

JOHN KRUSI, OF NEW YORK, N. Y., ASSIGNOR OF ONE-HALF TO ISAIAH SCHOFLER,
OF NEW YORK, N. Y.

EMBROIDERY-MACHINE.

1,089,418.

Specification of Letters Patent. Patented Mar. 10, 1914.

Application filed August 20, 1913. Serial No. 785,649.

To all whom it may concern:

Be it known that I, JOHN KRUSI, a citizen of the United States, residing at New York, in the county of New York and State of New York, have invented new and useful Improvements in Embroidery-Machines, of which the following is a specification.

My invention relates to embroidery machines and its object is to provide in machines of this character mechanism whereby a cord, braid, piping, chenille, threaded beads or other ornamental threads may be sewed to the material to be embroidered. The material is not passed through the needles, but is stitched on the surface of the fabric by means of the needles, which in case of being a braid will sew through the center of same and in case of being a cord the needle will operate first on one side then on the other in a zig-zag manner.

A further object of my invention is to provide means whereby the cord or other ornamental threads may be formed into any predetermined design or pattern and held in this position until sewed onto the fabric by the needle.

Another object of the invention is to provide means whereby the cord or ornamental thread may be formed into a complete circle, without said cord or thread being twisted around the needle, and thereby preventing its breaking.

Still another object of the invention is to provide automatic means whereby the cord or ornamental threads are automatically untwisted, relative to the needle whether the direction of the pattern runs from left to right or vice versa.

The invention further consists of parts and combinations of parts all more fully disclosed hereinafter and particularly pointed out in the claims.

Reference is to be had to the accompanying drawings, forming part of this specification in which similar characters of reference indicate corresponding parts in all the views and in which:

Figure 1 is a front elevation of an embroidery machine embodying my invention. Fig. 2 is a detached view of the left hand side of the machine, showing the tape actuating and cord guiding device, also the tension controlling mechanism. Fig. 3 is a plan view of the same. Fig. 4 is a sectional elevation, taken on line 4-4 of Fig. 2. Fig.

5 is a section on line 5-5 of Fig. 4, showing the mutilated gears. Fig. 6 is a detached view of the right hand side of the machine, showing one of the tape actuating and cord guiding devices. Fig. 7 is a plan view of the same. Fig. 8 is a sectional elevation on line 8-8 of Fig. 6. Fig. 9 is a fragmentary view of the pantograph and its connections. Fig. 10 is a side elevation of the upper part thereof. Fig. 11 is a sectional plan taken on line 11-11 of Fig. 9 looking in the direction of the arrow. Fig. 12 is an enlarged view, partly in section of the automatic reversing mechanism. Fig. 13 is a side elevation thereof, partly in section. Fig. 14 is a horizontal sectional view of the friction device. Fig. 15 is a transverse sectional elevation of the embroidery machine. Fig. 16 is an enlarged fragmentary front elevation of the presser foot. Fig. 17 is a cross-section thereof on line 17-17 of Fig. 16 with the cord guide in elevation. Fig. 18 is an enlarged cross-section of the presser-foot and cord guide, with the cord holder removed. Fig. 19 is a fractional plan view of the perforated steel tape used in turning the cord guides. Fig. 20 is a detached side elevation of the adjustable cord holder. Figs. 21-22-23-24 are vertical cross-sections of the presser-foot and guides, showing progressive steps in attaching the cord to the fabric. Fig. 25 is a view of a pattern to be embroidered. Fig. 26 is a series of diagrams, showing the progressive steps used in embroidering the pattern shown in Fig. 25. Fig. 27 is a diagrammatic view of the embroidery machine, showing to a better advantage its connections and automatic reversing mechanism, and Fig. 28 is another diagram of the machine showing a manually operated reversing device.

To the lower part of the free end of the pantograph 30 is attached the usual pointer 31 which serves as a guide to trace the pattern on the pattern board. This pointer is mounted to revolve in bearing 32 of said arm 30 and held in position by a collar 33 on the inside of the arm, and a bevel gear 34 on the outside. To this collar 33 is fastened a guide 33^a which has an outward extended portion 33^b adjacent to the pattern board, the object of this is to be explained later. Adjacent to the pointer 31 is the ordinary spacer or rest 31^a. At the lower end of arm 30 is the ordinary handle 30^a whereby the

pantograph 30 is moved. The bevel gear 34 fastened to the outer end of the pointer meshes into another bevel gear 35 which is fastened to the handle 36 and is revolubly mounted on the lower end of arm 30. Another bevel gear 37 meshes into gear 34 and is fastened to a short shaft 38 supported in a bearing 39. On the other end of said bearing a bevel gear 40 is secured to shaft 38 which meshes into a bevel gear 41 secured to shaft 42, mounted to revolve in bearings 43-43^a, fastened to arm 30. At the upper end of said shaft is a bevel gear 44 fastened thereto, and meshes into a gear 45 which is loosely mounted on a stud 46 which also serves as a connection of the pantograph. Integral with gear 45 is a sprocket wheel 47. This is best shown in Figs. 9-10. The object of the arrangement shown in Fig. 9 is to allow an unobstructed view of the pattern on the pattern board C.

Fastened to the frame A of the embroidery machine is the usual support 48 for the pantograph 30. Through the upper connection thereof passes a small shaft 49 which extends outward and serves as a trunnion for a sprocket wheel 50, which connects with sprocket wheel 47 by a chain 51. Integral with sprocket wheel 50 is another sprocket wheel 52 which connects with sprocket wheel 53 by a chain 54 to the tension controlling device, its purpose to be explained later. Integral with sprocket wheels 50-52 is a gear wheel 55 which meshes into a small gear 56, mounted to revolve on a stud 57, fastened to bracket 48. Integral with this small gear 56 is a large disk 58 with a serrated edge. Below this disk 58 is mounted a lever 59, fulcrumed at 60, on the standard 48. This lever 59 has at its upper end a spring pressed dog 61 which is always in engagement with the serrations of the disk 58. If the disk revolves in the direction of the arrow this dog will simply slip over the serrations, but in case of a reverse movement will take hold of the serrations and cause the lever 59 to reverse its position, shown best in Fig. 12. To the lower end of lever 59 is connected a rod 62 which connects to the upper end of lever 63, fulcrumed at 64 on a bearing 65, extended from the frame A. The lower end of this lever is connected to a clutch member 66 which slides on a feather 67 on the drive shaft 68 of the machine proper. This shaft is driven from the usual counter shaft 69 well known in the art.

On the drive shaft 68 are loosely mounted two bevel gears 70-71, these gears have at their inner sides, teeth 70^a-71^a, which register with teeth 66^a of the sliding member 66. Meshing into these gears 70-71 is another gear 72 which is fastened to a shaft 73, mounted to revolve in suitable bearings 74 supported from the frame A. At the upper

end of this shaft is fastened a gear wheel 75 and meshes into another gear 76 which is loosely mounted on shaft 77. The back of this gear 76 is flat and is held in contact with a leather washer 78 which fits between said gear 76 and a fixed collar 79 on the shaft 77. The outer end of said shaft is threaded to receive a hand wheel 80 and lock nut 81. Interposed between the hand wheel 80 and bevel gear 76, is a coil spring 82. When the tension on the spring 82 is properly adjusted, more or less friction may be had, between gear 76 and disk 79.

It will now be seen, by referring to Fig. 1, that when the operator turns the handle 36 of the pantograph in one direction of the delineated design on the pattern board, the guide 33^b following the pattern or direction of the line as closely as possible, the motion will be transmitted through the several gears and chains to shaft 106, it will also cause the small gear wheel 56 to revolve disk 58 and thereby actuate the lever 59 as before described. The object of having the disk 58 large is that a slight reverse movement of handle 36 will cause the reversal of lever 59. When said lever is moved into dotted position shown in Fig. 12 it will cause clutch member 66 to disengage from gear 71 and engage the clutch 95 on gear 70, thereby reversing the motion of shaft 73 and its connections. It will therefore be seen, that shaft 73 runs continually either in one direction or the other and that the motion to shaft 77 is transmitted through the friction drive B. By referring to Fig. 27 it will be seen that shaft 77 runs the whole length of the machine and is supported at intervals by suitable bearings 84.

At each end of the machine close to the inside of frame A are located transverse shafts 85-86, mounted to revolve in suitable bearings 87. These shafts are connected with shaft 77 with pairs of bevel gears 87^a-88 so as to run in opposite directions. At the forward ends of these shafts are fastened cams 89-90 which coöperate with rollers 91, fastened to slide in members 92-93, mounted to slide horizontally in brackets 94-95 fastened in suitable manner to frame A. On shaft 85 just back of bracket 94 is fastened a mutilated gear 96 meshing into another gear 97 which is fastened to a shaft 98 which revolves in suitable bearings 99, of the bracket 120 94, just above shaft 85. On shaft 98 is also fastened a worm-wheel 100, which meshes with a worm 101. This worm is fastened to a transverse shaft 102 and is supported by brackets 103 extended upward from bracket 125 94. At the outer end of shaft 102 is fastened a bevel gear 104, which meshes into another gear 105 on a horizontal shaft 106 which is supported from bracket 94 and mounted to revolve in suitable bearings 107. 130

At the forward end of this shaft is fastened a sprocket wheel 53. Just below shafts 85—86 and in line with the lower row of needles are mounted short shafts 108—109, 5 these shafts are mounted in suitable brackets 110—111 fastened to frame A. To the inner ends of these shafts are fastened sprocket wheels 112 and are driven from shafts 85—86 through chains 104—105 from 10 sprocket wheels 106—107 secured to shafts 85—86. On the outer end of shafts 108—109 are fastened cams 108a—109a.

The sliding members 92—93 fits into a dovetail groove of bracket 94 and is moved 15 back and forward by cams 89—90. The sliding members 92—93 extend inward toward the center of the machine and carries adjustable cross-bars 114—115. The outer ends of these bars are connected together by 20 a rod 116 and held tight by a screw and thumbnut 117. This rod 116 has loosely mounted rollers 118 which serve as guides for the cords 119 to the needles 120. The inner ends of cross-bars 114—115 are connected together with a perforated steel tape 25 121 which revolves the cord guides 122 and will be described later. It will be understood that there are two sets of these frame like structures, formed by the cross-bars 30 114—115, the rod 116 and the perforated tape 121, one in front of each row of needles. The cord guides 122 are made very thin in 35 shape of a ring with recesses 123 on each side, fitting into holes or bearings 124 in the presser foot 125 and are held in position by a cover 128 fastened thereto by screws 129. The cord guides 122 have at their periphery pins or teeth 126 meshing into holes 127 of 40 steel tape 121. The cord guides 122 have a small annular groove 130 at the inside, into which fits a ring 131, and is held from turning by frictional engagement. This ring is provided with different sized eyes 132 through which the different sized cords are 45 passed. The object of this ring is to get an easy adjustment of the cord, also to leave as much room as possible around the needle so as not to obstruct the view of the stitch. The perforated steel tape 121 is passed over 50 the cord guides 122 into the box like structure of the presser foot 125, so it will mesh in with the teeth 126, then it is passed under a small idler 133, then over another cord guide and so on. The object of the idler is 55 to give the tape a larger bearing on the cord guide. The usual apertures for the borers are shown at 134. The presser foot is fastened and driven by the machine in the usual manner. It will be seen that the 60 driving or oscillating mechanism for the cord guides is completely covered up, thereby preventing dust and lint making it inoperative.

From the foregoing it will be seen, that, 65 as the shaft 73 is driven continually in one

or the other direction, according to the rotation of the handle 36 of the pantograph 30, it transmits its motion to the friction disk B, and as the shaft 77 is locked from rotation by the worm 101 and worm gear 100 70 will cause the friction disk to slip, until the mutilated gears 96—97 are out of mesh, the shaft 77 will then be free to make one half revolution, this of course will turn shafts 85—86 as well as 108—109, thereby throwing the cams 89—90 and 108a—109a also one half revolution, the releasing occurs when the cam 89, see Fig. 2, is in a position shown 75 in dot and dash line to the left of shaft 85, and is instantly turned to the opposite position shown in dotted lines at the right of shaft 85 without losing any line in the working of the machine. The movement may be in either direction according to the direction of rotation of shaft 73. The cord carriers 122 will also make one half revolution thereby untwisting the cord 119 from the needle 120.

Referring to Figs. 7 and 15 it will be seen that the cord spools 135 are mounted to turn on standards 136 and the cord 119 is passed over pulley 118, thence into the eyes 132 of the cord guide 122. The threading of the needle is done in the usual way, the shuttle bar 137 is also of the usual construction. 90

Referring to Figs. 21—22—23 and 24 it will be seen that in starting the embroidery, the cord 119 is first passed through the eye on top, then back of the cord guide 122 and downward then outward through the lower eye 132. The machine is now ready to start and the needle will sew the cord to the fabric, owing to the fact that the cord comes right in front of the needle. In using a 105 round cord the needle is guided from one side to the other, as it would be impossible to strike the center, therefore a round cord would be sewn on the fabric, practically with "invisible stitches." 110

Assuming that a pattern like Fig. 25 is to be embroidered, the operation will be as follows:—Starting at *a* and working in the direction of the arrow, the cord 119 is at the top of the cord guide as shown at 138 in Fig. 26. The cord guide 122 is turned to the right until the cord 119 is at the bottom as shown at 139. It will now be seen that the cord 119 is half way twisted around the needle 120, at the next movement, or in other words, as the operator continues to turn the handle 36 in the same direction, the mutilated gears will get out of mesh and cause the cord guides 122 to be rotated one half revolution in the opposite direction, 125 bringing the cord 119 untwisted as shown at 140. As the operator continues to rotate in the same direction the cord carriers 122 also turn in the same direction as before until the top of the pattern is reached at *b*, 130

shown at 141 of Fig. 26, when it will be seen the direction of the arrows change. The operator now reverses the rotation of the handle 36, which will cause the reversal of 5 disk 58 and consequently will change clutch member 66 as before described. When the reversing has taken place it will reverse the rotation of the cord carriers, as shown at 10 142 and continue in this direction until the eye of the cord guide has reached the bottom shown at 143, this of course occurs at the bottom of Fig. 25. The mutilated gears are again unlocked and the cord carriers make another half revolution, only in the opposite 15 direction as before, and the twist is taken out of the cord as shown at 144. The operator turns handle 36 in the same direction as before, and of course the cord guides do the same until the top at *c* of the pattern 20 is reached, when the cord guide is in position shown at 145.

In Fig. 27 I have shown the serrated disk 58 in a different plane with a set of bevel gears in dotted lines, this is done to more 25 clearly bring out the connection.

Fig. 28 shows another diagrammatic view where the reversing of the shaft is done manually. A counter shaft 146 may be employed with two pulleys 147—148 driven in 30 different directions by belts. On the shaft 146 is a friction clutch 149 and ordinary clutches 150—151 which are operated through a bell crank 152 by a treadle 153. A sprocket gear fastened to the friction clutch 35 149 drives through a chain 153 another sprocket wheel 154 fastened to shaft 77. It will be seen that by shifting clutches 150—151, the shaft 77 will be caused to run in one or the other direction.

40 1. I claim:—

1. An embroidery machine comprising a pantograph, a rotator mounted thereon, carriers for guiding a cord to be sewed onto the fabric, means for oscillating the carriers, and means governed by the actuation of the rotator for controlling the oscillation 45 of the carriers.

2. An embroidery machine comprising a pantograph, a rotator mounted thereon, carriers for guiding a cord to be sewed onto the fabric, means for rotating the carriers, and means controlled by the actuation of the rotator for governing the rotation of the carriers.

55 3. An embroidery machine comprising a pantograph, a rotator mounted thereon, cord guides for guiding a cord to be sewed onto the fabric, means for rotating the guides, and means controlled by the actuation 60 of the rotator for reversing the rotation of the guides.

4. An embroidery machine comprising a manually operable pantograph, a rotator mounted thereon, cord guides for guiding a 85 cord over the fabric, means controlled by

the actuation of the rotator for interrupting and reversing the rotation of the guides.

5. An embroidery machine comprising a manually operable pantograph, a rotator mounted thereon, cord guides for laying a 70 cord onto the fabric, annular members carried by the guides for threading the cord, means for rotating the guides and means controlled by the actuation of the rotator for governing the rotation of the guides. 75

6. An embroidery machine comprising a manually operable pantograph, a rotator mounted thereon, a cord guide for laying a cord onto the fabric, an annular member having eyes of different diameters carried 80 by the guide for threading the cord, means for rotating the guide, and means controlled by the operation of the rotator for governing the rotation of the guide.

7. An embroidery machine comprising a 85 manually operable pantograph, a rotator mounted thereon, an annular cord guide for guiding a cord onto the fabric, an annular wire member fitted in the cord guide and having eyes of variable diameters for 90 threading the cord, means for rotating the guide, and means governed by the actuation of the rotator for controlling the rotation of the guide.

8. An embroidery machine comprising a 95 manually operable pantograph, a rotator mounted thereon, annular cord guides for guiding a cord onto the surface of a fabric, teeth formed on the periphery of the guides, a perforated tape adapted to engage the 100 teeth, mechanism for imparting reciprocating movement to the tape, and means governed by the actuation of the rotator for controlling the movement of the tape.

9. An embroidery machine comprising a 105 manually operable pantograph, a rotator mounted thereon, annular cord guides for laying a cord onto the fabric, teeth formed on the periphery of the guides, a steel perforated tape to engage the teeth, cams for 110 imparting reciprocating movement to the tape, and means controlled by the actuation of the rotator for governing the movement of the tape.

10. An embroidery machine comprising a 115 manually operable pantograph, a rotator mounted thereon, cord guides for laying a cord onto the fabric, teeth formed on the circumference of the guides, a steel perforated tape to engage the teeth, idlers for 120 tensioning the tape, cams for imparting reciprocating movement to the tape, and means controlled by the actuation of the rotator for governing the movement of the tape. 125

11. An embroidery machine comprising a manually operable pantograph, a rotator mounted thereon, cord guides for placing a cord onto the fabric, teeth formed on the circumference of the guides, a steel perfor- 130

rated tape to engage the teeth, means for adjusting the tape, idlers for tensioning the tape, and means governed by the actuation of the rotator for governing the movement 5 of the tape.

12. An embroidery machine comprising a manually operable pantograph, a rotator mounted thereon, cord guides for placing a cord on the fabric, teeth formed on the circumference of the guides, a perforated tape to engage the teeth, adjustable transverse bars for carrying the tape, sliding members mounted on the bars, cams to engage the sliding members, means for actuating the 15 cams, and means governed by the operation of the rotator for controlling the actuation of the cams.

13. In an embroidery machine the combination with a presser foot, of a series of annular cord guides journaled on the presser foot, teeth formed on the circumference of the guides, a perforated tape to engage the teeth, a cover secured to the presser foot for holding the guides in position and cover the 25 tape.

14. In an embroidery machine the combination with a series of cord guides, of a driving shaft for rotating the guides, clutch members carried by the shaft, a lever connected to the clutch members, a disk for actuating the lever, transmission shafts coupled to the disk, and manually controlled means for reversing the rotation of the disk.

15. In an embroidery machine the combination with a series of cord guides, of a driving shaft for rotating the guides, clutch members carried by the shaft, a lever connected to the clutch members, transmission 30 shafts connected to the driving shaft and the cord guides, a toothed disk, a lever connected to the first named lever and having a dog for engagement with the teeth of the disk and manually controlled means for reversing the rotation of the disk.

16. In an embroidery machine the combination with a series of cord guides, of a driving shaft for rotating the guides, clutch members carried by the shaft, a lever connected to the clutch members, transmission 40 shafts connected to the driving shaft and the cord guides, a lever connected to the first named lever, a disk for actuating the second mentioned lever, mutilated gears connected to the shafts and manually controlled means for reversing the rotation of the gears.

17. In an embroidery machine the combination with a series of cord guides, of a driving shaft for rotating the guides, clutch 50 members carried by the shaft, a lever con-

nected to the clutch members, a disk for actuating the lever, transmission shafts connected to the disk and the driving shaft, mutilated gears connected to the shafts, tension devices for regulating the rotation of 65 the transmission shafts, and means for reversing the rotation of the disk.

18. In an embroidery machine the combination with a series of cord guides, of a driving shaft for rotating the guides, clutch 70 members carried by the shaft, a lever connected to the clutch members, a disk for actuating the lever, transmission shafts connected to the disk and the driving shaft, mutilated gears actuated by the shafts, tension devices including worm gears for regulating 75 the rotation of the transmission shafts, and manually controlled means for reversing the rotation of the disk.

19. An embroidery machine comprising a 80 manually operable pantograph, a rotator mounted thereon, cord guides for positioning a cord onto the fabric, a driving shaft for rotating the guides, clutch members carried by the shaft, a lever connected to the 85 clutch members, a disk for actuating the lever, transmission shafts coupled to the disk and driving shaft, mutilated gears actuated by the transmission shafts, tension devices including worm gears for regulating 90 the rotation of the transmission shafts, and means controlled by the movement of the rotator for governing the rotation of the cord guides.

20. An embroidery machine comprising a 95 manually operable pantograph, a rotator mounted thereon, cord guides for positioning a cord onto the fabric, teeth formed on the periphery of the guides, a perforated tape to engage the teeth, transmission shafts 100 for imparting reciprocating movement to the tape, a driving shaft connected to the transmission shafts, clutch members carried by the driving shaft, a lever connected to the clutch members, a disk for actuating the 105 lever, transmission shafts coupled to the disk and driving shaft, mutilated gears, actuated by the transmission shafts, tension devices including worm gears for regulating the rotation of the transmission shafts, and means 110 controlled by the movement of the rotator for governing the rotation of the cord guides.

In testimony whereof I have hereunto set my hand in the presence of two subscribing 115 witnesses.

JOHN KRUSI.
